UNITED STATES PATENT OFFICE.

CHARLES A. FINLEY, OF BROOKLYN, NEW YORK, ASSIGNOR TO BOORUM & PEASE COMPANY, OF BROOKLYN, NEW YORK, A CORPORATION OF NEW YORK.

LOOSE-LEAF POST BINDER.

Application filed January 3, 1924. Serial No. 684,195.

My invention relates to loose leaf post binders and more particularly to post binders in which the posts project through the top clamping bar. The objects of my invention are to provide a binder which is light in weight, neat in appearance, economical in manufacture, efficient in use and which can be made in various sizes from one common stock of parts.

10 In the drawings,

Figure 1 is a perspective view of a binder embodying a modified form of my invention;

Figure 2 is a longitudinal sectional elevation of one end of the head of the binder;

15 Figure 3 is a section on the line 3—3 of Figure 2;

Figure 4 is a plan view in broken section of one end of the head of the binder;

20 Figure 5 is a perspective view of the two clamping bars with one of my self-contained post locks shown removed;

Figure 6 is a perspective view of the clutch member of my post lock;

25 Figure 7 shows the clutch member gripping the post, the relation being shown in a plan view and an elevation;

Figure 8 shows the relation of the clutch member and the post when the latter is free to pass therethrough, the relation being 30 shown in a plan view and an elevation;

Figure 9 is a perspective view disassembled of the preferred form of my invention; while

35 Fig. 10 is a longitudinal sectional elevation of one end of the head of the binder containing the preferred form of lock shown in Fig. 9.

In the type of binder to which my invention relates, the posts on which the sheets 40 are threaded project through the upper clamping bar and the latter has locking means on it adapted to prevent removal of the clamping bar unless the mechanism is released.

45 For clamping bars I employ non-metallic strips 10 made for example of wood, fibre, rubber or composition, making them thick enough so that my post lock 11 can be let in flush in the upper bar by simply cutting 50 a separate opening therein, such as a hole or notch, for each lock. I shall first describe the application of my invention shown in Figures 1 to 8. In this form of binder the bar is notched as shown in Fig. 5 to receive 55 the post lock 11 which fits in the notch with

its top flush with the top of the bar. The post lock is covered by a casing 12 which can be fastened to the bar by rivets 13. These rivets also serve to make the ends of the bar rigid. A cover 14 may be attached 60 to the upper clamping bar by making use of hinge lugs 15 each of which form a unitary part of one of the casings. For post members I have shown rigid sectional posts 65 screwed into sleeves 17 which in turn 65 are set into the lower clamping bar. To prevent these sleeves 17 from turning or coming out, the tip of the sleeve is squared on two sides, a plate 18 fitted onto the shoulders thus formed and the plate fastened 70 to the clamping bar (see Fig. 5). These plates 18 are also employed to form hinge lugs 19 by which means a cover 20 is attached to the lower bar.

The upper bar has holes 21 bored therein 75 to permit the posts to pass through. I find however that continued removal and replacement of the upper clamping bar tends to wear away these holes 21 because the bar is not made of metal and therefore I prefer 80 to put in a metal eyelet 22 which is peaned over on the top and bottom of the bar (see Figures 2 and 5).

The independent and individual one-way locks 11 for the posts each have a frame 85 23 mounted in its casing 12 and a swinging clutch 24 pivoted in the upper part of the side walls of the frame. By a one-way lock, I mean a lock which will permit the cover 90 to be pushed down on the papers in the binder but will not allow the cover to be pulled off the post. The post 16 passes through a polygonal opening 28 in one end of the clutch, which opening is a little larger than the post. This end of the clutch is 95 heavier than the other end and therefore the clutch tends to assume the position shown in Figure 7 and grip the post. I prefer to employ a spring adapted to press 100 the post end of the clutch down and thus assist gravity in keeping the clutch in engagement with the post, and in the drawings this is shown as a bow spring 25, (Fig. 4). On the end of the clutch opposite to the posts rests a button 26 projecting through 105 a hole 27 in the frame, which is held in said frame by a flange larger than and underlying the hole. This button, in the illustration of the invention shown in the drawings, also projects through the casing 12, 110

and serves as means for releasing the clutch. The openings in the frame 23 and casing 12 through which the post passes are preferably made larger than the posts because the clutch itself grips the post on both sides and does not depend on the openings for any wedging action. I also prefer to make the frame 23 a little deeper than is necessary for the clutch to grip and release the post, because by incorporating this additional feature posts of different diameters can be used without in any way hindering the operation of the locks. This feature of permitting the clutch to swing down further than is necessary to grip the post ordinarily, has the additional advantage that the clutch will grip the post even if the cover is being pushed down unevenly on the two posts so that the upper clamping bar 10 is not parallel to the lower clamping bar.

To put on the top cover and clamping bar, it is only necessary to thread the posts through the openings in the clutch, frame and casing, and push the clamping bar down. The clutch will not catch on the post while doing this because the latter tends to push it up to the horizontal position and thus obtain the benefit of the full width of the polygonal opening 28. However the post cannot pass downward through the clutch for the opening in the clutch would be tipped with relation to the post and the edges (I have shown four) would grip and hold the post. It will be apparent that the more one attempts to pull the clamping bar off without releasing the clutch the more it will bind on the posts.

To release the one-way locks and remove the clamping bar, the buttons 26 are depressed, thus bringing the clutches horizontal and releasing the posts, when the bar can be pulled off. I prefer to locate the buttons between each post and the nearest end of the clamping bar, thus permitting the operator to release the clutches and pull up the clamping bar all in one movement.

In the preferred form of my invention shown in Figs. 9 and 10 a round lock is employed. To apply this form of lock to the upper clamping bar of a binder one need only bore a round hole through the bar, insert the lock from the bottom and fasten it in by screws passing through the bottom plate.

My invention has many advantages over the prior art. It does away entirely with metal tubes and their associated elements such as end caps, rivets, covers, etc., and

produces a handsome, simple device. My invention does away with all necessity for machine-like precision in spacing the posts and making them to exact size, and also produces a binder in which the locks operate properly even when the binder becomes deformed. Furthermore binders of all sizes can be easily and economically made up from one common stock of bar material and locks. The employment of a solid non-metallic bar and my novel independent locks let in flush in the bar produces a cheap, economical and handsome binder which has no projecting parts of any kind and is convenient to operate.

I claim—

1. In a loose leaf post binder, a solid clamping bar and posts adapted to project therethrough, in combination with an independent lock for each post associated with said clamping bar, and a hinge lug unitary with said lock.

2. In a loose leaf post binder, a solid clamping bar and posts adapted to project therethrough, in combination with an independent lock for each post let in substantially flush in said clamping bar, and a hinge lug unitary with each lock.

3. A loose leaf post binder, having a solid clamping bar and posts adapted to project therethrough, in combination with an independent one-way lock for each post let in substantially flush in said clamping bar, and a hinge lug unitary with each lock.

4. As a new article of manufacture, an independent self-contained lock adapted to be let into the clamping bar of a loose leaf binder and to grip a post of the binder, said lock comprising a frame, a swinging clutch pivoted in the side walls of said frame and having an opening near one end adapted to grip a post therein, in combination with releasing means for said clutch operable from the top of the frame, and a hinge lug unitary with said frame; substantially as described.

5. In a loose leaf post binder, a solid clamping bar having holes extending clear through the same, and posts adapted to project therethrough, in combination with an independent lock for each post adapted to fit into each hole, and a hinge lug unitary with said lock, adapted to be fastened to the bottom of the bar, substantially as described.

In testimony whereof I have signed my name to this specification.

CHARLES A. FINLEY.
